UNITED STATES PATENT OFFICE.

CLARENCE R. CHELLEW, OF PEORIA, ILLINOIS.

FASTENER FOR RECEPTACLE COVERS.

1,104,035.

Specification of Letters Patent.

Patented July 21, 1914.

Application filed February 6, 1911. Serial No. 606,813.

To all whom it may concern:

Be it known that I, CLARENCE R. CHELLEW, a citizen of the United States, residing at Peoria, in the county of Peoria and State 5 of Illinois, have invented certain new and useful Improvements in Fasteners for Receptacle-Covers, of which the following is a specification.

This invention has reference to a new and 10 improved fastener, which is especially useful as a means for clamping a transparent cover to jars or cans containing fruits, vegetables and the like.

The invention has for its object to improve 15 the manner of displaying and showing the contents of cans or jars containing fruits, vegetables and the like.

It is the custom for travelers representing 20 large jobbers and wholesalers of canned goods to carry with them cans containing the various goods to be sold. To display 25 the same to a dealer, the salesman must cut open the cans, which are afterward inconvenient to carry and are usually left with the dealer, a loss to the jobber, and if carried will soon spoil and slop over. With my 30 invention, the goods may remain in the original package, or packages especially provided, which may have a transparent cover, so that one may view the contents, or be easily removed, whereby the contents may have closer inspection or removed. The fastener for clamping the covering being simple, and effective in use, and adjustable to all 35 sizes of cans or jars.

That the invention may be more fully understood, reference is had to the accompanying drawings, in which:

Figure 1 is a side elevation showing a can 40 or receptacle containing fruit or vegetables, with my fastener applied thereto to clamp the transparent closure thereon, one fastener in the act of being clamped in position; Fig. 2 is a face view of a clamp, and the can or receptacle to which it is attached; Fig. 3 is a vertical section of one-half of a can or receptacle and also of the fastener attached thereto; Fig. 4 is a cross-section in plan of the body of one of the fasteners, as the same 45 would appear on the line 4—4 of Fig. 2, and Fig. 5 is an enlarged longitudinal section of the fastener, omitting the spring and cam-lever.

Like characters of reference denote corresponding parts throughout the figures.

The fasteners, as will be understood, are

preferably used in pairs, to be applied to a can or receptacle on diametrically opposite sides thereof, see Fig. 1. The description therefore of one will suffice for both. It is 60 to be understood however, that one of these devices can be used efficiently where the cover of the receptacle is very small.

The fastener comprises a plate 6, which is of suitable length and width to adapt it 65 to be applied to various height cans, jars or receptacles, and may be stamped out of sheet-metal or otherwise conveniently formed. At the lower end of the plate 6 it is provided with the diverging feet 7, extending obliquely from the body of the plate to adapt them to the convex surface of the can, jar or receptacle, see Fig. 4, and the lower ends of the feet are bent inwardly at right angles at 8, which are adapted to be 70 located beneath and engage the bottom of the can, jar or receptacle. The upper portion of the plate is provided with guiding members or clips 9 and at a suitable point beneath the lowest guiding member or clip 80 a lug 10 projects outwardly from the plate, and beneath the lug 10 there is an opening 11 in the plate. Slidable in the guiding members or clips 9, is a stem 12, which has the threaded opening 13 therein for a portion 85 of its length at its upper end and formed with the tubular opening 14 for a portion of its length at its lower end, the extreme lower portion of the stem being split forming the bifurcated ends 15. When the stem 12 is in 90 operative position in the guiding members or clips 9 of the plate 6, the lug 10 on the plate 6 projects through the stem between the bifurcated ends 15, see Figs. 2 and 3, the stem being adapted to be moved up and down 95 across the face of the lug. A spring 16 is carried in the tubular opening 14 of the stem, bearing against the lug 10, while between the bifurcated ends 15 and below the lug 10 there is pivotally attached to the stem 100 12 a cam lever 17. The lever being fulcrumed at 18 and its cam surface 19 adapted to ride or bear against the lower face of the lug 10, when the lever 17 is moved downward, which will cause the stem 12 to be forced downwardly against the action of the spring 16. Swinging the lever 17 upward and outward allows the spring 16 to expand, forcing the stem 12 downwardly. Having a threaded relation with the threaded opening 13 in the stem 12 is a supplemental member in the form of a stem or rod 19^a, 105 110

bent at right angles at its outer end, as at 20, the end of the portion 20 being covered with rubber 21 or other soft and resilient material.

5 The can, jar or receptacle is designated A, the top having been opened, or perhaps formed with an opening, leaving an annular ring B.

C designates a transparent closure or covering for the can or receptacle which has an outer annular recess D to receive a gasket E, which will lie against the ring B of the can when the closure or covering is placed over the open end.

15 In operation, the supplemental arm or rod 19 is adjusted with relation to the stem 12, by screwing or unscrewing the same in the threaded opening 13 in stem 12. The plates 6 are then placed alongside the can or receptacle, preferably diametrically to each other, with the portions 8 of the feet 7 beneath the can to engage the bottom thereof. The stem 12 and arm or rod 19^a are swung around bringing the parts 20 and engaging means 21 over the top of the cover or closure C, see Fig. 1, when the levers 17 are thrown down, which will move the stems 12 downward producing an impinging relation between parts 21 and closure C, locking or 25 clamping the closure C firmly over the open end of the can. By this means the contents of the receptacle may be viewed through the closure and access easily had to the contents for purposes of sampling, and the receptacle 30 again easily and quickly sealed and the receptacle and contents carried from place to place without slopping out.

The fasteners, as will be observed, are adjustable to different sizes of cans, jars and 40 receptacles and are easily and quickly attached, removed or readjusted.

It is obvious that the fastener may be modified in various ways and either stamped or formed out of sheet metal, which would 45 slightly modify the present construction, without, however, departing from the spirit and scope of the invention.

What I claim is:

1. A fastener for the cover of a receptacle, comprising a plate having feet to extend beneath and engage the bottom of the receptacle, a member movable longitudinally on said plate and adapted to engage the top of the cover, a lever for locking the movable member against the cover, and means for releasing the movable member when the lever is released.

2. A fastener for the cover of a receptacle, comprising a plate having feet to extend beneath and engage the bottom of the receptacle, a member adjustably connected with said plate and movable longitudinally on said plate for engaging the top of the cover, means for causing an impinging relation 65 between said adjustable member and cover,

and means for releasing said adjustable member from said cover, when said last mentioned means is released.

3. A fastener for the cover of a receptacle, comprising a plate having feet to extend beneath and engage the bottom of the receptacle, a member movable longitudinally on said plate, cover engaging means having an adjustable connection with said movable member, and means for operating said movable member.

4. A fastener for the cover of a receptacle, comprising a member having means to engage the bottom of the receptacle, a stem movably carried on said member, a cover engaging member having an adjustable connection with said stem, a lever for moving the stem to lock the member against the cover, and a spring operating to release the cover engaging member when the lever is released.

5. A fastener of the character described, comprising a plate, a stem movably attached to said plate, a lug attached to the plate and extending into the stem, a lever fulcrumed on the stem and adapted to engage the lug for moving the stem, a spring in the stem bearing against the lug, and a cover engaging member adjustably connected with said stem.

6. A fastener of the character described, comprising a plate having extending feet, a stem movably attached to said plate, a lever pivoted to said stem and having a cam engagement with the plate for moving the stem in one direction, a spring for moving the stem in the opposite direction, and a supplemental member having an adjustable connection with said stem, the free end of said supplemental member being bent at right angles.

7. In a device of the character described, a plate adapted to extend along a receptacle and engage the bottom thereof, guiding members or clips on said plate, a stem slideable in said guiding members or clips, a lever for moving said stem relative to said plate, said stem having a rod or arm connected thereto and adapted to engage the top or cover of a receptacle.

8. In a device of the character described, a plate adapted to extend along a receptacle and engage the bottom thereof, guiding members or clips on said plate, a stem slideable in said guiding members or clips, a cam lever for moving said stem relative to said plate, and a rod or arm adjustably connected to said plate and adapted to engage the top or cover of a receptacle.

9. In a device of the character described, a plate adapted to extend along a receptacle and engage the bottom thereof, guiding members or clips on said plate, a stem slideable in said guiding members or clips, a spring between said plate and stem adapted to

force said stem upwardly, a cam lever operatively connected with said plate and stem and adapted to be operated to force said stem downward against the pressure of said

5 spring and a rod or arm connected to said stem and adapted to engage the top or cover of a receptacle.

10. In a device of the character described, a plate adapted to extend along a receptacle and engage the bottom thereof, guiding members or clips on said plate, a lug or projection on said plate, a stem slidable in said guiding members or clips and having a rod or arm connected thereto, a cam lever pivotally mounted on said stem and adapted to be moved to engage said lug or projection to move said stem relatively to said plate.

15 11. In a device of the character described, a plate adapted to extend along a receptacle and engage the bottom thereof, guiding members or clips on said plate, a lug or projection on said plate, a stem slidable in said guiding members or clips and having a rod or arm connected thereto, said stem having its lower portion bifurcated to receive said lug or projection and having a tubular opening above said bifurcated portion, a spring in 20 said tubular opening adapted to engage said stem and said lug or projection, a cam lever pivotally mounted in said bifurcated portion of said stem and adapted to be moved to engage said lug or projection to move said stem relatively to said plate.

25

said bifurcated portion of said stem and adapted to be moved to engage said lugs or projection to move said stem relatively to said plate.

12. In a device of the character described, a plate adapted to extend along a receptacle and engage the bottom thereof, guiding members or clips on said plate, a lug or projection on said plate, a stem slidable in said 30 guiding members or clips and having a rod or arm connected thereto, said stem having its lower portion bifurcated to receive said lug or projection and having a tubular opening above said bifurcated portion, a spring in 35 said tubular opening adapted to engage said stem and said lug or projection, a cam lever pivotally mounted in said bifurcated portion of said stem and adapted to be moved to engage said lug or projection to move said 40 stem relatively to said plate.

In testimony whereof I affix my signature, in presence of two witnesses.

CLARENCE R. CHELLEW.
